UNITED STATES PATENT OFFICE

154,139

DESIGN FOR A LOCOMOTIVE BODY OR THE LIKE

Ray Patten, Norwalk, Conn., assignor to General
Electric Company, a corporation of New York

Application October 12, 1946, Serial No. 133,898

Term of patent 3½ years

(Cl. D66—1)

To all whom it may concern:

Be it known that I, Ray Patten, a citizen of the United States, residing at Norwalk, in the county of Fairfield, State of Connecticut, have invented a new, original, and ornamental Design for a Locomotive Body or the Like, of which the following is a specification, reference being had to the accompanying drawing, forming a part thereof.

In the drawing, Fig. 1 is a fragmentary front perspective view of the locomotive body or the like embodying my new design; Fig. 2 is a front elevational view of the design shown in Fig. 1; Fig. 3 is a fragmentary top plan view of the design shown in Figs. 1 and 2 and Fig. 4 is a side elevational view of a locomotive body equipped with a locomotive front end and cab the same as that shown in Figs. 1, 2 and 3. The other side is the same as that shown. The characteristic features of my design reside in the portions shown by means of full lines.

I claim:

The ornamental design for a locomotive body or the like, substantially as shown and described.

RAY PATTEN.
